UNITED STATES PATENT OFFICE.

ANDREWS ALLEN, OF GLENCOE, ILLINOIS.

DRAFT MECHANISM FOR MINE CARS.

Application filed April 8, 1922. Serial No. 550,576.

My invention relates to draft mechanism for mine cars and has particular reference to a draw bar mounting having a centering arrangement whereby the coupler head is projected forward parallel to the longitudinal axis of the mine car and having means associated therewith adapted to hold the coupler head in a horizontal plane so that the coupling head is always projected forward so as to engage with and enter the female coupler of the opposite mine car and yet may be moved out of its normal position by external force applied thereto, and will return to normal position as soon as such force is removed.

A further object of my invention is the provision of a mine car coupling having a flexibly mounted coupler shaft which, in order to effect a coupling upon a curve, can be pulled out of alignment and to engage with a female coupler by provision of a flaring open mouthed female coupler head upon mine cars of the type shown in my copending application, Serial No. 543,150.

These and further objects of my invention will be more fully and better understood by reference to the accompanying sheets of drawings wherein—

Figure 1 is a plan view of my improved invention showing the forward spring fully compressed;

Figure 2 is a longitudinal vertical view, partially in section and partially in elevation, of the parts shown in Figure 1 showing the forward spring fully compressed;

Figure 3 is a vertical transverse sectional view through Figure 2;

Figure 4 is a detail plan view of the coupler block shown in Figure 1; and

Figure 5 is a detail view showing the triangularly shaped projection on the lower end of the lower trunnion of the coupler block adapted to center the coupling member.

Referring now specifically to the drawings and in which like reference characters refer to like parts throughout a section of a pair of mine car bottom plates 10 and 11 is shown to which a pair of upwardly extending Z-bars 12 and 13 is connected, a top plate 14 being secured to the Z-bars 12 and 13 which forms the upper side of the coupling box within which the coupler shank is mounted. A pair of longitudinally extending downwardly projecting angles 15 and 16 is provided which are connected to the plates 10 and 11 on their under sides, the angles 12 and 13 and the top plate 14 heretofore described forming the complete coupler box within which the mechanism is mounted and which is secured to the center sill 17 of a mine car in the usual manner, a pair of angles 18 and 19 being provided which extend vertically of the coupler box and are secured to the Z-bars 12 and 13 and the angles 15 and 16, the said coupler box being open at its lower side to facilitate the removal of the coupler shank and connecting means. Extending transversely across the coupler box and permanently secured to the plate 14 by means of rivets 28 and the Z-bars 12 and 13 is a member 20 having a recess 21 therein within which the upper trunnion 22 on the coupler block 23 is seated. The coupler block 23 is circular in form and has an elongated opening 24 therethrough which is flattened at its lower side 25 and upon which a coupler shank 26 rests, the lower side 27 of the coupler shank 26 being also slightly flattened so as to rest upon the flattened surface 25 of the coupler block 23, the drawings (Figure 3) showing these surfaces slightly out of contact with each other for better purposes of illustration. The coupler shank 26 has the usual coupler head 29 formed integrally with said coupler shank 26 or separate therefrom, as may be desired, with an opening 30 therein through which a coupler pin passes when the mine cars are coupled together. Mounted upon the coupler shank 26 in front of the coupler block 23, is a spring 31 seated within a cup-shaped member 32 adapted to form a housing for the spring 31 and to receive excessive coupler shocks, as hereinafter described. Around the coupler shank 26 is a spring 31, abutting against the container 32 at one of its ends and the coupler block 23 at its other end, the said spring 31 holding the cup member 32 against an angular shoulder 33 formed upon the coupler shank 26 so that the cup 32 is properly held in position upon the coupler shank 26. The spring 31 is shown in the drawing in compressed position with the end of the cup-member 32 resting against the coupler block 23, the purpose of the cup-member 32 being to retain the spring 31 in position and to receive the coupling shocks after the spring 31 has been partially compressed. A spring 34 is mounted upon the coupler shank at the rear of the coupler

block 23 with a cup-member 35 having a recess 36 therein within which the spring 34 is seated with a counterweight portion 37 extending downward below the coupler shank 26, so that the weight of the cup-member 35 assists in retaining the coupler head in a horizontal plane. A pair of lock nuts 38 and 39 are in threaded engagement with the coupler shank 26 at its rear end and are screwed up tightly enough so that each of the springs 31 and 34 are under a slight tension when the coupler mechanism is at rest. The cup 35 is adapted to receive the excess pulling strains to which the coupling 10 may be subjected or to sudden jerks in excess of the resistance offered by the spring 34 so that the springs 31 and 34 will not be set by constant and severe strains imposed upon them through the pulling and pushing of the mine cars. A carrier 40 is provided having an enlarged portion 41 having a recess therein within which the lower trunnion 43 on coupler block 23 is seated the said carrier being secured to the angles 15 and 16. 20 A triangular shaped recess 44 is provided in the enlarged portion 41 of the carrier 40 at the bottom of the recess 42 and within which a triangular shaped projection 45 on the trunnion 43 is seated, the projection having two rearwardly inclined flat surfaces 46 and 47 with a sloping edge 48 which, when the coupler block 23 is in normal position, rests upon the parallel inclined flat surfaces 49 and 50 respectively of the recess 44 so that any turning movement of the coupler shank 26 and the coupler block 23 causes the edge 48 to ride upon one or the other of the inclined surfaces 49 or 50, lifting the coupler block and coupler shank a slight distance so that when the strain is removed, the coupler block 23 is turned back into its normal position. A slight space is provided at the upper end of the trunnion 22 so that the block 23 can be easily lifted. The carrier member 40 has its ends positioned between a plurality of stops 51 and 52, secured to the angles 15 and 16, and has projecting portions extending laterally therefrom through which bolts 56 pass which serve to hold the carry-iron 40 in proper position. The bolts 56 have removable keys 57 extending therethrough so that with the removal of the keys 57, the carrier member 40 can be dropped down and the entire coupler mechanism removed from the car. The coupler shank 26 and coupler block 23 can be assembled outside of the car and then the whole structure placed in position within the coupler box and then the carry-iron 40 placed in position in the coupler box which holds the structure in position in the mine car.

It will thus be understood that the coupler head 29 can be moved laterally to either side if force is applied to the coupler head, but because of the camming action between

the angularly disposed surfaces of the projection 43 and the recess in the carry-iron, the coupler head will be automatically returned to normal and retained in a line of direction at right angles to the carry iron 40 and the counterweight 37 will keep the coupler head 29 in a horizontal position so as to insure proper and efficient coupling of the mine cars. The coupler shank will rotate in the coupler block so that the mine cars can be dumped in the usual rotary dumping apparatus in common use at coal mines for dumping the mine cars.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. Draft mechanism for mine cars comprising in combination a draw bar, a coupler block having trunnions thereon through which the said draw bar extends, one of said trunnions having a projection thereon having angularly disposed surfaces, an upper retaining member within which one of said trunnions is mounted, a lower carry-iron within which the lower trunnion is mounted, the said lower carry-iron having a recess therein having angularly disposed sides corresponding to the angular sides of the projection on the said trunnion when the coupler head is projecting forward from the said coupler block at right angles thereto.

2. Draft mechanism for mine cars comprising in combination a draw bar, a coupler block through which the said draw bar extends, the said coupler block having upper and lower trunnions thereon, a retaining member within which the said upper trunnion is mounted and a carry-iron connected to said mine car within which the said lower trunnion is mounted, the said lower trunnion having a projection thereon extending into a recess formed in the said lower carry-iron, the contour of the said recess and of the said projection corresponding with each other when the draw bar extends through the said coupler block in a direction at right angles thereto.

3. Draft mechanism for mine cars, comprising in combination, a draw bar, a coupler block through which said draw bar extends having trunnions at its upper and lower sides, an upper retaining member having a recess therein in which the upper trunnion is seated, and a removably mounted carry-iron having recesses therein within which the lower trunnion is seated, the said lower trunnion having means associated therewith to normally hold the coupler shank in a line,

parallel to the longitudinal axis of the mine car.

4. In combination with a coupler, a coupling head having rearwardly extending 5 coupler shank, a coupler block through which said coupling shank extends having upper and lower trunnions thereon, a retaining member in the upper coupler housing having a recess therein within which the upper 10 trunnion is seated, a carry-iron having a central recess therein with a triangular shaped recess in the lower part of said central recess, the said lower trunnion having a triangular shaped projection thereon seated 15 within the said triangular shaped recess, whereby upon a lateral turning movement of said coupler block, it will automatically turn to normal position.

5. Draft mechanism for mine cars, comprising in combination, a draw bar, having 20 a coupler head thereon and a shank extending rearwardly therefrom, a coupler block through which said shank extends having upper and lower trunnions thereon, a retaining member above said coupler block having 25 a recess therein within which the upper

trunnion is seated, a removable carry-iron having a recess therein within which a lower trunnion is seated, and means adapted to normally retain said coupler block in a vertical plane at right angles to the longitudinal axis of the mine car. 30

6. Draft mechanism for mine cars, comprising in combination, a draw bar having a coupler head thereon and a shank extending rearwardly therefrom, a coupler block through which said shank extends having upper and lower trunnions thereon, a retaining member secured to the mine car within which said upper trunnion is seated 35 and a carry-iron having a recess therein within which said lower trunnion is seated, the said lower trunnion having a downwardly projecting triangular shaped member integrally formed therewith which seats 40 in a cooperating triangular shaped recess formed in said carry-iron whereby the said draw bar is normally maintained parallel to the longitudinal axis of the mine car. 45

Signed at Chicago, Illinois, this 4th day 50 of April, 1922.

ANDREWS ALLEN.
